(57) **CLAIM**

The ornamental design for a divider member for display shelf, as shown and described.

DESCRIPTION

FIG. 1 is a side plan view of a divider member for display shelf showing our new design; and,
FIG. 2 is a front view thereof.

FIG. 1 is shown broken away and understood to indicate that no particular length is claimed.
The broken lines that can be seen in FIGS. 1 and 2 are used to represent environmental subject matter and form no part of the claimed design.
